UNITED STATES PATENT OFFICE.

ROBERT S. OLIVER, OF NEW HAVEN, CONNECTICUT, ASSIGNOR TO THE ANDREW B. HENDRYX COMPANY, OF NEW HAVEN, CONNECTICUT, A CORPORATION OF CONNECTICUT.

DESIGN FOR A BIRD-CAGE BODY.

Application filed June 13, 1929. Serial No. 31,661. Term of patent 14 years.

To all whom it may concern:

Be it known that I, ROBERT S. OLIVER, a citizen of the United States, residing in New Haven, New Haven County, Connecticut, have invented a new, original, and ornamental Design for a Bird-Cage Body, of which the following is a specification, when taken in connection with the accompanying drawings, of which—

Fig. 1 is an elevation of a bird cage body showing my new design; and

Fig. 2 is a top plan view thereof.

I claim:

The ornamental design for a bird cage body substantially as shown.

ROBERT S. OLIVER.
